UNITED STATES PATENT OFFICE.

LOUIS HERZOG, OF BEACON, NEW YORK, ASSIGNOR TO GLENHAM EMBROIDERY COMPANY, OF BEACON, NEW YORK, A CORPORATION OF NEW YORK.

JACQUARD-CARD REPEATING AND TRANSPOSING MACHINE.

1,423,110.

Specification of Letters Patent. Patented July 18, 1922.

Application filed September 1, 1920. Serial No. 407,428.

To all whom it may concern:

Be it known that I, Louis HERZOG, a citizen of the United States, and a resident of Beacon, in the county of Dutchess and State 5 of New York, have invented certain new and useful Improvements in Jacquard-Card Repeating and Transposing Machines; of which the following is a specification.

My invention relates to machines for repeating jacquard cards for use in embroidering machine jacquards or automats. In machines of this class the operation of the machines is controlled by means of a jacquard card previously made on a manually controlled punching machine, the previously made card serving as a master to control the punching of one or more similar cards in the repeating machine. Heretofore, the cards made on the repeating machines have been exact duplicates of the master card. The object of my present invention is to provide means not only for repeating or reproducing copies of the master card but also for transposing the perforations in the card which is being punched in order that when the new card is used to control the jacquard of an embroidery machine the design produced by the embroidery machine will be transposed as compared 25 to a design produced by the original or master card.

In making various embroidered designs it is often desirable to transpose or rearrange the same figure or design and heretofore it 35 has been necessary to punch an original jacquard card for each position of the design and this entailed considerable labor. If, for instance, a flower is to be embroidered on the four corners of handkerchiefs on the well 40 known Swiss embroidery machines, it is desirable to arrange the flower or design for each corner and heretofore it has been customary to make a separate jacquard card for each corner design because the card 45 which is adapted to make the design for the left corner could not be used for making the design for the right corner and the cards for making the upper corners could not be used for making the bottom corners; and 50 consequently an original card had to be made for each separate corner although the design, except for its position, was the same throughout. The device forming my present invention is adapted to transpose the

perforations in repeating a jacquard card 55 whereby a master card which is made for producing a design in an upright position, for instance, may be repeated and automatically transposed so that the copied card will effect the production of the design in 60 an inverted position, or vice versa. It is therefore not necessary to make by manual operation two original or master cards for producing the design in upright and inverted positions as the one may be automatically made from the other. The present machine may also be used for repeating without transposing, thus serving the function of an ordinary repeating machine, but the invention relates to the transposing features. 70

In my copending case Ser. No. 407,429 filed concurrently herewith I have shown a machine for transposing from right to left, i. e., for turning a design over from right to 75 left or vice versa. That device is adapted to be used in conjunction with the present one for producing any desired transposition. Where both devices are employed it is possible to make one master card by manual operation for a corner design for say, the upper left hand corner of a handkerchief, and then the cards for making the design for the other three corners may be automatically made from the first master by 80 transpositions produced in the machine of my said copending application and in the present machine. Preferably, certain parts of that machine and the present one are made interchangeable so that the one machine, except for the parts which are 85 changed, may be used for the entire work.

In transposing from an upright to an inverted design, or vice versa, it is necessary to transpose the perforations in the jacquard 95 card which control the direction slides of the jacquard and the present device is intended to effect the necessary change in the perforations to cause the design to be changed from an upright to an inverted position or vice 100 versa.

In the drawings forming part of this application,

Figure 1 is a diagrammatic view of a piece of embroidery showing the effect upon the 105 embroidered fabric of the transpositions brought about in the present machine.

Figure 2 is a horizontal sectional view

through a machine embodying my invention in the preferred form,

Figure 3 is a plan view of the slides and their frame,

5 Figure 4 is a sectional view showing the platens and punches, and part of the means for effecting transposition of the direction controlling perforations,

Figure 5 is a plan view thereof, and

10 Figure 6 is an end elevation of the devices shown in Figure 3.

Many of the parts of the present machine correspond with those of the machines heretofore used and I will describe herein only 15 so much of the entire machine as is necessary to teach those skilled in the art the present improvements. Generally, repeating machines include needles which are acted upon by the original or master jacquard card, 20 these needles being reciprocated or remaining stationary at each operation of the machine, according to whether any particular needle meets with a solid portion of the master card or aligns with an aperture 25 therein. In the drawings I have shown a bank of needles 1 which reciprocate horizontally in the slide frame 2. The needles 1 are staggered as in the well known Groebli system, in order that the perforations across 30 the card may be arranged closer together than the size of the needles or punches will permit and the jacquard card makes two reciprocations for each complete transverse row of perforations and it is advanced the 35 distance between the upper and lower needles in Figure 6 between two of the reciprocations, as in present practice. These needles 1 are the elements or members which are directly acted upon by the master jac- 40 quard card for controlling the perforating of the repeated card. The master card 3, arranged upon a roller (not shown) passes partly around the slotted roller 4, being ad- 45 vanced step by step by the latter. The arm 5 rocking on a pivot 6 has a pawl 7 for en- 50 gaging notches in a ratchet wheel fixed on the shaft 8; and the arm 5 is rocked by a pitman 9. The latter is rocked by a lever arm 11 and the upper end of the latter has 55 a roller 12 engaging in a cam groove 13 in a cam 14 arranged on the main shaft 15. At each revolution of the cam 14 the pawl 7 is rocked to turn the shaft 8 and the roller 4 to advance the master pattern card one 60 position or the distance between the two rows of needles 1.

The strip 16 which is being punched travels between the punch blocks 17, 18, and then between the rollers 19, 20 the former 65 having feed pins 21 for engaging in the feed perforations of the card; and these rollers serve to feed the repeat card step by step in time with the feeding of the master card. There is an arm 22 on the shaft 23, 70 which arm is pivoted to a link 24 and the

other end of the link is pivoted to an arm 25. The opposite end of the arm 25 is ar- 75 ranged on the shaft 26. There is a pawl 27 carried by the arm 25 and it engages a ratchet on the shaft 27^a for the purpose of 70 rotating the rollers 19, 20 to feed the card 16 step by step. There is a detent 28 on the arm 25 which also engages the teeth of the ratchet when the pawl 27 disengages there- 75 from, for the purpose of preventing the shaft 27^a from turning when the pawl 27 is out of the ratchet.

The shaft 8 of the master card roller 4 is carried upon arms 29 which are pivoted at 80 30. There is an arm 31 loose on the shaft 8 and the lever arm 32 is pivoted at one end to the shaft 33. The arm 34 on the latter shaft is connected by a pin and slot connec- 85 tion 35 with an arm 36 on the shaft 37. The lever arm 38 is fixed to the shaft 37 and it has a roller 39 engaging in the groove 13 of the cam 14 on the main shaft. The rock- 90 ing of the lever arms 38, 36 and 34, 32 causes the arms 29 and roller 4 to swing toward and from the several needles.

The punches 40, 41 are arranged in aper- 95 tures in the upper and lower punch blocks 17, 18 and they have collars 42 by means of which the upper punch block may return all those punches which pass through the card 95 which is being punched. The upper punch block 17 is raised by means of a link 43 pivoted to the lever arm 45 and to the arm 36 on the shaft 37. The arm 45 at 47 en- 100 gages with and raises the punch block 17 as the shaft 46 is rocked.

The punches 40, 41 are arranged in two rows in order to get the perforations on the card close together but the perforations made by the two rows of punches are 105 brought into one line by the advancement of the card between operations. As this conforms to present practice further details of the operations need not be set forth herein.

110 Each punch is controlled by an individual platen 48, these platens sliding at right angles to the planes of the punches in a frame 49 which is provided with apertures in the bottom to receive the upper ends of 115 the several punches. Each platen is pro- 120 vided with a recess or notch 50 in its bottom edge and when a platen is positioned to bring its notch in register with the corre- 125 sponding punch that punch will not be locked and therefore it will not perforate the card 16 as it will not be forced down. When a platen is positioned with its notch 50 away from its particular punch that punch will be forced down with the frame 125 49 and that particular punch will perforate the card.

The punch frame 49 is carried upon links 51 which are pivoted to arms 52 projecting forwardly from the shaft 53 to which they 130

are fixed. The shaft 53 is rocked through an arm 54 fixed at one end thereto and having a roller 55 on its opposite end which travels in the groove of the cam 14. The 5 platen frame 49 is thus periodically lowered and raised to cause the several punches to perforate the jacquard card.

The plateaus 48 are moved backwardly or to the right in Figure 2 by the master card 10 and they are mechanically returned after each operation by the following means. There are links 56 loosely journaled on the shaft 53 and at their lower ends they carry a plate 57 which engages the rear ends of 15 the several platens 48 for the purpose of moving them forwardly. There is a rod 58 pivoted to an eye 59 on the plate 57 and this rod has a yoke 60 on its forward end which straddles and is guided by the main 20 shaft 15. There is a roller 61 on the end of this rod 58 which is operated by the cam 62 on the main shaft for drawing back the bar 58 and the plate 57, springs 63 serving to move these parts forwardly. At each revolution 25 of the main shaft 15 the bar 58 and plate 57 are drawn backwardly by the cam 62 and then the bar and plate are drawn forwardly by the springs 63. As the plate 57 moves backwardly, or to the right in Figure 30 2 it permits any of the platens to be moved backwardly and as the plate 57 moves forwardly it returns the platens back to their original positions.

The parts thus far described correspond 35 with present practice and my present improvements relate to the devices for modifying the punching operations to cause certain transpositions in the punching operation.

On the shaft 64 there are forwardly extending arms 65 which carry a movable 40 shaft 66 which is adapted to be swung downwardly and upwardly when the shaft 64 is rocked; and a hand lever 67 is adapted to swing this latter shaft to place the transposing device into or out of operation. There are several fingers 68 hung from the 45 shaft 66 and they have yokes 69 which straddle the latter and permit the fingers to move horizontally relatively to the shaft 66 though the fingers rise and fall with the latter. On certain of the platens (four as shown) there are fixed guides 70 through 50 which the fingers 68 project and in which they are adapted to slide vertically. These 55 fingers 68 are adapted to be lowered into position to lie between certain of the platens and the slides 71 which operate these particular platens, for a purpose which will be set forth hereinafter. The rocking of the 60 shaft 64 by the handle 67 serves either to project the lower ends of the fingers 68 between the slides 71 and platens or else to withdraw them, according to whether perforations are to be transposed or whether 65 the master card is to be copied exactly.

The use of the fingers 68 necessitates a modification in the platen returning device and for this purpose I have provided slots 72 in the forward edge of the plate 57 in line with the platens on which the fingers 70 68 operate. These slots allow certain platens to move back to a position to the rear of the remaining platens but they are only used when the machine is used for transposing. There is a plate 73 attached to the 75 plate 57 by thumb screws 75 threaded into the plate 57 and passing through slots in the plate 73. The plate 73 has slots 74 which are adapted to register with the slots 72 in the plate 57 when the machine is used 80 for transposing but when the plate 73 is moved to the right to the position shown in Figure 5 the slots 74 in the plate 73 are no longer in register with the slots 72 in plate 57 and consequently all platens will be 85 returned to corresponding position when the returning plate 57 goes forwardly.

The needles 76 engage the feed pins 77 on the roller 4 which operates the master pattern and these needles reciprocate their respective slides 71 each time the needles strike the feed pins 77 of the roller 4 the same as in present practice. The slide 71 thus operated effects the operation of corresponding platens and punches for punching the feeding apertures in the card being punched. Beyond the feed punching needles 76 there are certain needles 78 and slides which effect the punching of perforations to control the operation of special 90 function devices in the embroidering machine but since these are not necessarily altered by the application of my present invention further description of them is 95 unnecessary.

Between the needles 76 there are 32 needles 1, in the embodiment of my invention shown, and where the device is to be used in conjunction with the Groebli jacquard these needles may be considered as 100 representing four groups each containing 8 needles. The seven needles 79 of each group are adapted to control the perforations which effect the coupling of the moving devices in the jacquard; and where the 105 card is to be used in a Groebli jacquard the perforations made through these needles control the slides *j* in the patent to Groebli, No. 528,632 and thereby effect the coupling of the slides *G'* and the slides *m*—*m'* in 110 said patent to cause the movement of the tambour frame of the embroidering machine varying extents. The perforations made through these needles correspond with the master card as in transposing the 115 design from upright to inverted or vice versa only the perforations for the direction slides need be transposed. For each group of needles there is a direction controlling needle these being shown at 80 and count- 120 125 130

ing from left to right in Figure 3 they are the first, ninth, seventeenth and twenty fifth needles of the whole series. These needles determine the direction of motion 5 of the tambour frame moving devices of the embroidering machine and the perforations effected in the card by them control the coupling of the members J, D^s in the said Groebli patent and thereby determine 10 whether the members which move the tambour frame are to move right or left hand. In the present case the perforations in the master card controlling the movement slides of the jacquard are copied on the punched 15 card but the perforations controlling the direction slides of the jacquard are transposed, so that where a perforation appears on the master there will be a solid portion on the corresponding position in the reproduced 20 card and where there is a solid portion in the master card there will be a perforation in the corresponding position in the reproduced card.

The needles 80 are connected with the 25 slides 71 which control certain platens 48 and these latter are the platens with which the fingers 68 are associated and which are affected by the slots 72, 74 in the plates 57 and 73.

30 Operation: If the machine is to be used for ordinary repeating, that is, for repeating an exact copy of the master card without transposing any of the perforations then the handle 67 is swung to raise the 35 fingers 68 so that they do not affect the operation of any slides or platens. The plate 73 in such case is clamped in such position that its slots 74 are out of register with the slots 72 of the returning plate 57. The machine 40 will then operate as an ordinary repeating machine and every perforation in the master card will be reproduced the same in the repeated card.

When, however, the machine is to be operated for transposing, the following changes 45 will be made. The plate 73 will be adjusted to bring its slots 74 in register with the slots 72 of the plate 57 and the screws 75 will be again tightened to keep the plate 73 in this 50 position. The several slots 74, 72 of the plates 73, 57 will be in line with the platens 48 which control the punches for making the perforations controlling the direction slides in the jacquard. The handle 67 will be 55 moved to rock the shaft 64 and this will lower the fingers 68 so that their lower ends are interposed between the ends of the slides 71 and the forward ends of the corresponding 60 platens 48.

60 A master card having been placed around the roller 4 and a blank card having been threaded between the punch blocks 17, 18 and the rollers 19, 20 the machine will operate as follows: Starting with the slides, 65 needles and the platens all in their forward

position, the roller 4 will be swung back toward the needles by the rocking of the lever arms 38, 36, 34, 32, 31 actuated by the cam 14 on the main shaft. The master card will be pressed against the rows of needles 1 70 and those needles which contact with a solid portion of the master card will, with their respective slides, be forced backwardly; whereas, those needles which are in line with perforations in the master card will remain 75 idle. The needles and slides are thus operated in accordance with the master card. Before this operation takes place all the platens 48 which are operated by the needles 79 are in a forward position with their slots 80 50 out of register or forward of the respective punches, which is the initial position. If the machine were not being used for transposition the platens 48 controlled by the needles 80 would be in corresponding positions, but as operated for transposing, the platens 48 controlled by needles 80 will be in a position behind the remaining platens with their rear ends projecting into the slots 74, 72 in the plates 73, 57. In the above described operation the needles 79 which are moved back by the master card will move their corresponding platens back and this will bring such platens into position with their slots 50 in line with the respective 95 punches. However, the slides in line with the fingers 68, i. e., the direction slides will, because of the interposition of the fingers 68, move their corresponding platens back to positions beyond the other platens and this 100 is permitted by the slots 72, 74 in the plates 73, 57. The platens which are thus moved back by the needles 80 will have their slots 50 moved away from their respective punches, which is the reverse of the other 105 platens.

After the roller 4 and master card have been reciprocated, the frame 49 and upper punch block move down and the punches which have been locked by their platens will 110 be forced through the repeat card. The frame 49 will then move up again and all the platens which were moved back before will be moved forward again by the return of the returning plate 57. The platens operated by the needles 79 will be returned to a 115 position with their slots 50 out of register with their respective punches but owing to the slots 72, 74 in the plates 57, 73 the platens operated by the needles 80 will be returned 120 to positions with their slots 50 over the respective punches.

In the above operations the fingers 68 are forced back with the slides which are moved back and they are moved forward again 125 when the respective platens 48 are moved forwardly. The yokes 69 permit these fingers 68 to thus move in relation to their supporting shaft.

In the above operation the needles 79 130

which entered apertures in the master card were not moved and therefore their platens remained forward and locked their respective punches so that these punches were forced through the repeat card and formed perforations exactly as in the master card. Whereas, the needles 80 which alined with apertures in the master card were not moved and their respective platens were left with their slots 50 in register with the respective punches and those needles 80 which met solid portion of the master card forced their respective platens back to positions to lock the respective punches. Therefore, the direction punches formed perforations in the repeat card where there were solid portions in the corresponding positions on the master card and they left the repeat card unperforated in positions where there were perforations in the master card.

After each punching operation the roller 4 and master card are moved forward again and the roller 4 is turned by the pawl 7 to bring a new line of perforation in line with the several needles. Also, the rollers 19, 20 and repeat card 16 are advanced one step by the pawl 27. The above operations are repeated until the whole card has been punched.

The repeat card will now have perforations for movement slides exactly like the master card, but the perforations for the direction slides of the jacquard will be reversed, i. e., where there is a perforation in the master card there will be a solid portion in the repeat card and vice versa. When the repeat card is used in the jacquard the movement slides will be operated the same as if the master card were used and the extent of each movement of the embroidering machine tambour frame will be the same. The direction slides will be operated just the reverse of what they would if the master card were used and the result will be that the tambour frame will be moved upwardly where it would otherwise be moved downwardly and it will be moved downwardly where it would otherwise be moved upwardly, the extent of movement remaining the same in each case. The effect of this on the embroidering machine is to transpose or invert the design.

By reference to said Groebli patent it will be seen that the tambour frame of the embroidering machine is operated by diagonal members which act upon a roller on the tambour frame which always lies at the point where the members cross each other. If the member B (Fig. 4) in said Groebli patent is operated to the right the tambour frame will be moved obliquely downwardly and to the right. If the same member B is moved to the left the tambour frame will be moved obliquely upwardly to the left. The change of direction of the member B therefore inverts the movement of the tambour frame. This is also true of the member C. It is also

true that where both members B and C are operated simultaneously and if the direction of movement of both be reversed, then the resultant movement of the tambour frame will be inverted. In the card punched by the present device every movement of the members B and C in the Groebli patent as represented in the master card is reversed in direction so that if the master card is adapted to cause the production of the design A in Figure 1 of the present drawings the repeat card will produce the design B in said figure when the cards are employed in the said Groebli jacquard.

The present invention is very simple as very few additional parts are required to convert the ordinary repeating machine for transposing.

Having described my invention, what I claim is:

1. In a jacquard-card repeating machine the combination of selecting members adapted to be actuated by a master jacquard card and members for perforating the repeat card, controlled by said selecting members, certain of said selecting members being adapted to control the perforations affecting the extent of movement devices in an embroidering machine jacquard, and others of said selecting members being adapted to control the perforations affecting the direction of movement devices in the jacquard, means for actuating corresponding perforating members, according to the operation of said selecting members which control the extent of movement devices, and means for causing the transposition in the operation of certain other perforating members by said selecting members which control the perforations for the direction of movement devices of the jacquard.

2. In a jacquard-card repeating machine the combination of selecting members adapted to be actuated by a master jacquard-card for controlling the perforation of apertures in the repeat card for controlling the extent of movement devices in an embroidering machine jacquard, other selecting members for controlling the perforation of apertures in the repeat card for controlling the operation of direction devices in the jacquard, members for perforating the repeat card, operated by said selecting members, and means for reversing the operation of the said second selecting members on their respective perforating members whereby perforations will be made in the repeat card where there are solid portions in corresponding positions in the master card and solid portions where there are perforations in corresponding positions in the master card.

3. In a jacquard-card repeating machine the combination of means for perforating the repeat card to control the extent of movement devices in an embroidering machine

- 6 jacquard and members for perforating the repeat card to control the direction of movement devices in the jacquard, selecting members operated by a master jacquard card 5 for controlling the operation of said perforating members and means for effecting the operation of certain of said second perforating members by certain of said selecting members according to the perforations 10 of the master card and adapted to be adjusted to effect a reversal in the actuation of said second perforating members by their selecting members for the purpose set forth.
4. In a jacquard-card repeating machine 15 the combination of perforating members adapted to perforate the repeat card, platens for locking the perforating members for operation, slides, actuated by a master jacquard-card for selecting the platens for operation, and means adapted to be interposed between certain of said slides and their corresponding platens for reversing the operation of said platens on their respective perforating members.
- 25 5. In a jacquard-card repeating machine the combination of perforating members adapted to perforate the repeat card, platens for locking the perforating members for operation, slides actuated by a master jacquard 30 card for selecting the platens for operation, and members adapted to be interposed between certain of said slides and their corresponding platens for reversing the operation of said platens on their respective per-
- forating members, and adapted to be moved 35 with said platens and slides.
6. In a jacquard-card repeating machine the combination of perforating members adapted to perforate the repeat card, platens for locking the perforating members for operation, slides actuated by a master jacquard-card for selecting the platens for operation and means for reversing the operation of certain of said platens on their respective perforating members, including 40 45 guiding means mounted on certain of said platens, and movable means having fingers slideable in said guiding means, said fingers being movable in relation to said movable means whereby they may move with the 50 slides and platens.
7. In a jacquard-card repeating machine the combination of perforating members adapted to perforate the repeat card, platens for locking the perforating members for operation, slides actuated by master jacquard-card for actuating the platens in one direction, means for returning said platens, including adjustable means for returning certain of said platens different extents than 55 60 others of said platens, and means adapted to be interposed between certain of said slides and their corresponding platens for reversing the action of said platens.

Signed at Beacon in the county of Dutchess and State of New York, this 9th day of August, 1920.

LOUIS HERZOG.
